UNITED STATES PATENT OFFICE

HARRIET BACHLEDA, OF MINNEAPOLIS, MINNESOTA

HAIR MARCELLER

Application filed October 15, 1927. Serial No. 226,383.

My invention relates to toilet accessories and has particular reference to devices for curling, marcelling, or waving the hair, the object of the invention being to provide a device of this character which is relatively light in weight, easily applied and removed and which will produce a more permanent waving or curling of the hair than is accomplished by the use of the devices heretofore proposed in the art.

A further object of the invention is to provide a hair curler of this character which is exceedingly simple and practical in construction, yet which will be strong, durable and efficient in use, which will not injure the hair, and which is relatively inexpensive to manufacture and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a perspective view of the device in position for receiving a strand of hair,

Figure 2 is a similar view showing the main hair retaining bar in locked position,

Figure 3 is a similar view showing the main and supplemental hair retaining bars in locked position, and

Figure 4 is a transverse sectional view taken substantially along a line 4—4 of Figure 3.

Referring now to the drawing in detail, the invention comprises a substantially elongated rigid plate member 5, of a slightly arcuate formation between the ends thereof, from each end of which extends a pair of spaced parallel rods 6, each of said rods being in longitudinal alinement with the edges of the plate member 5 and with the outer ends of the rods at each end of the plate connected by a transverse rod 7.

A main hair retaining bar 8 is disposed beneath the plate member 5 in longitudinal alinement therewith, with one end of said bar curved about the transverse rod 7 at one end

of the plate member 5 whereby to provide a hinged mounting for the bar 8. The bar 8 is curved in conformity with the plate member 5 and with its free end terminating adjacent the plate rods 6 at the end of the plate member 55 remote from its pivotal connection and arranged for engagement by a catch 9 carried by said spaced rod.

To the transverse rod 7 pivotally supporting the bar 8 is also pivotally connected one end of a link 10, the opposite end of said link forming a pivotal connection with a pair of relatively thin spring steel rods 11 adapted to extend longitudinally of the plate member 5 with the bar 8 interposed between the plate 65 and said rod.

As clearly illustrated in Figures 1 and 2 of the drawing the link 10 is of a relatively short length and adapted to space the rods 11 from the bar 8 so that upon arranging 70 the strands of hair as shown at 12 in a clamping position between the plate member 5 and bar 8 as shown in Figure 2, the rods 11 will engage the hair at a point remote from the portion so clamped.

The rods 11 may also be brought together to clamp the hair extending from each side of the bar 8. One of the rods 11 is provided with a catch 12 for engaging the other of said rods whereby to secure the same together. The transverse rods 7 at the end of the plate member opposite from the link 10 carry a swinging cap 13 within which the free ends of the rods 11 may be extended upon the movement of the link 10 and rods 85 11 upwardly against the underside of the bar 8 whereby to retain the parts in position as shown in Figure 3 of the drawings.

When the parts are secured in this position the strands of hair will be securely 90 retained to form a double curl or marcel therein as clearly illustrated in Figure 4 of the drawings. The plate member 5 and the rods 11 may be provided with a covering of rubber as shown at 14 whereby to prevent injury to the hair upon the contact of the same with such parts of the device.

It is apparent that any desired number of the devices constructed in accordance with my invention may be attached to the hair of 100

a person to produce a series of curls in the form of marcelling through the hair.

It is obvious that my invention is susceptible to various changes and modifications in construction without departing from the spirit of the invention or the scope of the appended claims, and I accordingly claim all such forms of the device to which I am entitled.

10 Having thus described my invention, what I claim as new is:

1. A hair curler of the class described comprising a plate member, a hair retaining bar pivotally attached at one end to said plate member, a catch carried by said plate member engageable with the free end of the bar whereby to secure said bar against the plate member whereby to retain the strands of hair therebetween, a link pivotally carried at the pivoted end of said bar and a pair of rods attached at one end to said link whereby to space the adjacent ends of the rods and the bar from each other a substantial distance, said rods coacting with each other for clamping a separate portion of the hair and independent means carried by said plate member for engaging and retaining said rods in superposed relation at one side of the plate.

2. A hair curler comprising a plate member having spaced parallel rods extending outwardly from each end thereof and connected at their outer ends by a transverse rod, a hair retaining bar pivotally attached at one end to one of said transverse rods, a catch at the opposite end of the plate member for engaging the free end of the bar and retaining the same against one side of the plate, a link also pivotally attached to said transverse rod at the pivoted end of the bar, a pair of relatively thin spring steel rods pivotally connected at one end to said link and extending longitudinally with respect to the bar, means for securing the spring steel rods in closely spaced relation for clamping the hair therebetween and a rod supporting member carried by the other of said transverse rods adapted to retain the spring steel rods and said link in longitudinally extended relation against the side of the bar opposite from the plate.

HARRIET BACHLEDA.
